UNITED STATES PATENT OFFICE.

RICHARD LAVERY, OF BOSTON, MASSACHUSETTS.

METAL-BENDING MACHINE.

SPECIFICATION forming part of Letters Patent No. 450,241, dated April 14, 1891.

Application filed June 20, 1890. Serial No. 356,078. (No model.)

To all whom it may concern:

Be it known that I, RICHARD LAVERY, of Boston, county of Suffolk, State of Massachusetts, have invented an Improvement in 5 Metal-Bending Machines, of which the following description, in connection with the accompanying drawings, is a specification, like letters on the drawings representing like parts.

This invention relates to machines used for 10 bending metal; and has for its object to improve and simplify the construction of the same, whereby they are adapted to a more general class of work and capable of a more convenient and finer adjustment. In ship 15 construction the angle-irons which are to form the frame of the ship are first shaped and beveled while hot, but in cooling, and also in the process of punching the holes for the rivets, the angle-irons become more or 20 less distorted, it being necessary to afterward recurve them while cold, my improved machine being particularly adapted to this latter operation. In accordance with this invention the metal, in bar or other form, is supported upon a table or bed in front of two or 25 more properly-shaped pins or blocks, between which the bar is subjected to the action of a reciprocating block or head, adjustably mounted on a threaded rotatable shaft carried 30 by and made movable with a sliding head reciprocated from a crank or eccentric on the usual main shaft, suitable means being provided by which to rotate the said threaded shaft to regulate the position of the 35 said reciprocating block or head thereon. The pins or blocks referred to, against which the bar is placed, and also the reciprocating block or head, are formed to present a number of different shapes to accommodate varying 40 shapes of metal to be curved.

One part of my invention therefore consists in the combination, with the bed and a shaft carried thereby, of a head adapted to be reciprocated from the said shaft, a threaded 45 shaft movable longitudinally with said head, and a bending-block adjustably mounted on the said threaded shaft, to operate substantially as will be described.

Other features of my invention will be hereinafter pointed out in the claims at the ends of 50 this specification.

Figure 1 shows in plan view a metal-bend-

ing machine embodying this invention; Fig. 2, a side elevation of the same; Fig. 3, a longitudinal section taken on the dotted line xx , 55 Fig. 1; Fig. 4, a right-hand end elevation of Fig. 1; Figs. 5 and 6, sectional details taken respectively, on the dotted lines $x'x'$ and $x''x''$, Fig. 1; and Figs. 7, 8, 9, and 10, details to be referred to. 60

Referring to the drawings, the bed A of the machine, supported on suitable standards A', has suitable bearings for the main shaft a , having fast thereon the gear-wheel a^1 , meshing with the pinion a^3 , fast on the counter-shaft a^4 , mounted in suitable bearings carried by one of the standards A', and provided with a pulley a^5 , driven by a belt not shown. The main shaft a is provided at its middle with a crank or eccentric a' , preferably of 70 short throw, on which is journaled one end of the connecting-rod b , jointed at its opposite end to the head c , fitted to slide on suitable guides c' , formed in the bed A, (see Fig. 5,) so that when the shaft a is rotated the head 75 c will be slowly reciprocated. The head c is represented as formed of two halves or members bolted together and inclosing loosely between them the collars d' on the threaded rotatable shaft d , fitted at its outer end to slide 80 freely through a hole in the bed A and to receive outside thereof a hand-wheel d^2 , by which to rotate the said shaft. The threaded shaft d receives upon it the block e , provided with flanged guides e' , and fitted to slide in 85 suitable guideways formed in the bed A, (see Fig. 6,) the said block at its upper part having upon opposite sides the vertical dovetail grooves 2, which receive the dovetail projections 3 on the former-blocks f . (See Figs. 1 90 and 7.) The bed A of the machine is provided with a number of holes h to receive the shanks h' of the removable pins or blocks h^2 , which may be circular in cross-section. The bar m to be bent is placed upon the table or 95 bed, as shown in Fig. 1, and in front of the pins h^2 , the bar to be bent or straightened being herein represented as a piece of angle iron or steel.

Upon starting the machine the block e is 100 reciprocated slowly, and by turning the hand-wheel d^2 in one direction said reciprocating block is brought forward on the threaded shaft d with relation to the head c , so that said

block will strike against the bar at each forward movement, springing the same and giving a slight "set" at each movement, the amount of spring and permanent set being 5 regulated by turning the hand-wheel d^2 . If the bar is straightened or bent too much, or if it is desired to bend a bar in the opposite direction, it may be shifted to or placed at the opposite side of the reciprocating block e and 10 the hand-wheel d^2 turned in the opposite direction to carry the reciprocating block e back on the threaded shaft d to cause said block to strike against the bar from the opposite side thereof at each backward movement, 15 springing the same and giving to it a slight set in the opposite direction to thereby bend or unbend the same as required.

In modern iron-work, particularly ship construction, it is customary to use what is known 20 as "Z-bars," of iron or steel. These bars, as well as the angle-bars previously referred to, are first shaped while hot and punched, and in most cases are beveled or opened out, making them flatter, as shown in Figs. 9 and 10, 25 to adapt them to the lines of the ship. These bars must also be recurved after they have become cooled, and in order to do this without destroying the sectional angles, I have provided pins or blocks h^2 , (see Figs. 7, 8, 9, 30 and 10,) embodying a number of different shapes, as s s' s^2 , to engage the beveled Z-bars top and bottom only, so as to preserve the proper angles while curving the same. When the bar is placed upon the bed, the 35 pins h^2 are turned until the proper section s is presented to the bar to engage it top and bottom opposite the horizontal flanges.

It is obvious that the pins h^2 may be provided with sections s adapted to a bar of any 40 shape whatsoever.

By the construction shown the machine is capable of an adjustment limited only by the length of the threaded shaft d , which gives great range of adjustment.

45 I do not herein claim, broadly, the combination, with two pins to support the bar, of a reciprocating head to act on the metal between the pins.

I claim—

50 1. The combination, with the bed, pins or blocks thereon, and a shaft carried thereby, of a head adapted to be reciprocated from the

said shaft, a threaded shaft movable longitudinally with said head, and a bending-block provided with two opposite bending-faces adjustably mounted on the said threaded shaft, the said head and bending-block when reciprocated moving in a line between the said pins or blocks, substantially as described. 55

2. The combination, with the bed A, pins or blocks thereon, and a shaft a supported thereby, of a head adapted to be reciprocated from the said shaft on a line between the said pins or blocks, the threaded shaft d , rotatable in and movable longitudinally with said head, 60 the block e , provided with two opposite bending-faces adjustably mounted on the said shaft d , and the wheel d^2 on said threaded shaft, to operate substantially as described. 65

3. In a machine for bending metal, the combination, with the bed having holes h and the reciprocating block e , of pins or blocks for said holes formed to present sections of different shapes, substantially as described. 70

4. The bed A and pins or blocks thereon, 75 and a shaft a , provided with a crank, combined with a pitman b , head c , consisting of two halves or members, the rotatable threaded shaft d , loosely held in said head, and the block e , adjustably carried by said shaft, to 80 operate substantially as described.

5. In a metal-bending machine, a bed, a shaft carried thereby, a table on which the metal to be bent is placed, and pins or blocks thereon, combined with a head adapted to be reciprocated from the said shaft, a threaded shaft placed below the surface of said table 85 and movable longitudinally with said head, and a bending-block adjustably mounted on said threaded shaft and projecting laterally above the surface of said table, whereby the reciprocating movement of said bending block in either direction may be utilized for bending the metal, the said head and bending-block when reciprocated moving in a line 90 between the said pins or blocks, to operate 95 substantially as described.

In testimony whereof I have signed my name to this specification in the presence of two subscribing witnesses.

RICHARD LAVERY.
